UNITED STATES PATENT OFFICE

149,086

DESIGN FOR A CHICKEN PICKING
FINGER UNIT

Bert T. Norman, Los Angeles, Calif., assignor to
Selwyn B. Holley and Vernal M. Holley, Los
Angeles, Calif.

Application June 5, 1946, Serial No. 130,427

Term of patent 3½ years

(Cl. D11—1)

To all whom it may concern:

Be it known that I, Bert T. Norman, a citizen of the United States, residing in Los Angeles, in the county of Los Angeles and State of California, have invented a new, original, and ornamental Design for a Chicken Picking Finger Unit, of which the following is a specification, reference being had to the accompanying drawing, forming part thereof.

Fig. 1 is a side elevational view of a chicken picking finger unit, showing my new design.

Fig. 2 is an end elevational view.

Fig. 3 is a top plan view.

I claim:

The ornamental design for a chicken picking finger unit, substantially as shown.

BERT T. NORMAN.
